(57) **CLAIM**

I claim the ornamental design for a bottle with cap, as shown and described.

DESCRIPTION

FIG. 1 is a perspective view of a bottle with cap showing our new design;

FIG. 2 is a front elevational view thereof, the left side, right side, and rear elevational views thereof being identical thereto;

FIG. 3 is a top view thereof; and,

FIG. 4 is a bottom view thereof.

The broken lines in the drawings illustrate portions of the article that form no part of the claimed design.
